UNITED STATES PATENT OFFICE

HENRY A. PICKARD, OF CHICAGO, ILLINOIS

DESIGN FOR A BORDER STRIP FOR SERVICE WARE

Continuation of design application Serial No. 30,948, filed April 19, 1929. This application filed November 16, 1929. Serial No. 33,459 $\frac{1}{2}$. Term of patent 7 years.

To all whom it may concern:

Be it known that I, HENRY A. PICKARD, a citizen of the United States, residing in Chicago, in the county of Cook and State of Illinois, have invented a new, original, and ornamental Design for Border Strip for Service Ware, of which the following is a specification, a continuation of application Serial No. 30,948, filed April 19, 1929, reference being had to the accompanying drawings, forming a part thereof, in which—

Figure 1 is a plan view of the border, as applied to a plate, which is shown in dotted lines, it being understood that the design shown is continued throughout; and

I claim:

The ornamental design, for a border strip for service ware as shown and described.

HENRY A. PICKARD.
